UNITED STATES PATENT OFFICE.

WILLIAM A. IVES, OF NEW HAVEN, CONNECTICUT.

BIT-BRACE.

SPECIFICATION forming part of Letters Patent No. 301,058, dated June 24, 1884.

Application filed April 28, 1884. (No model.)

To all whom it may concern:

Be it known that I, Wm. A. IVES, of New Haven, in the county of New Haven and State of Connecticut, have invented a new 5 Improvement in Bit-Braces; and I do hereby declare the following, when taken in connection with the accompanying drawings and the letters of reference marked thereon, to be a full, clear, and exact description of the 10 same, and which said drawings constitute part of this specification, and represent, in—

Figure 1, a side view of the body with the sleeve thereon; Fig. 2, a side view of the body and jaws, showing the sleeve in section; 15 Fig. 3, a vertical section of the jaws and body; Fig. 4, a modification.

This invention relates to an improvement in that class of bit-braces which consist of a pair of jaws arranged in a socket upon which 20 a surrounding sleeve is provided, so as to be drawn onto the jaws by a corresponding screw-thread on the body of the brace, whereby the jaws are forced to engage the tang of the bit—a common and well-known class of 25 bit-braces. As more generally constructed, these jaws are arranged loosely in the body of the brace, and a spring or other device provided to automatically open the jaws when relieved from the pressure of the surrounding sleeve.

The object of my invention is to make the jaws a fixed part of the body of the brace, and give to their tails sufficient elasticity to automatically open when relieved from the 35 pressure of the sleeve; and the invention consists in constructing the jaws with elastic tails made fast in or substantially a part of the solid body, combined with a surrounding sleeve screw-threaded, corresponding to the 40 screw-thread on the said body of the brace, as more fully hereinafter described.

A represents the body of the brace, to which the handle is fixed in the usual manner. It is cylindrical in shape, and screw-threaded upon its exterior, and upon this 45 the sleeve B is fitted, as shown, and as in the usual construction.

C C are two jaws, which I make from steel or other suitable metal having a degree of 50 elasticity, and construct them each with a tail, D. The body A is cast upon the tails of the jaws, so as to be firmly united thereto,

as seen in Fig. 3. This is best accomplished by forming a mold corresponding to the body of the brace and the jaws, the two jaws then 55 laid into the jaw part of the mold, their tails extending into the body portion. Then the metal poured into that body portion of the mold will surround and unite with the tails of the jaws, so as to as firmly secure the 60 parts together as if made in one and the same piece. This construction is very much cheaper than the jaws and body can be made if forged complete from steel. The jaws and body A may be made complete in one and the 65 same piece—say as cast from steel—and in which the jaws would be an integral part of the body. The jaws automatically open, owing to the elasticity of their tails, so that when free they stand in the position seen in Fig. 2. 70 The interior of the sleeve is dome-shaped, so as to bear upon the nose end of the jaws, and so that when the sleeve is run onto the body it will force the jaws together to grasp the bit-brace in the usual manner. The adjacent 75 faces of the two jaws are recessed in the usual manner to form a seat for the tang of the bit. In some classes of braces the sleeve is arranged to operate upon the jaws in the opposite direction to that shown in Fig. 2—that is, as seen in Fig. 4. Such construction necessitates only a reverse incline to the backs of the jaws, as shown in that figure.

I claim—

1. The herein-described improvement in 85 bit-braces, consisting of the solid cylindrical body A, screw-threaded upon its cylindrical surface, the jaws C C, with their elastic tails D D united to said body in the process of manufacture, whereby said jaws become substantially an integral part of the body, combined with a surrounding sleeve, B, internally screw-threaded, corresponding to the 90 screw-thread on the body, substantially as described.

2. The jaws C, forged with their tails D D, and with the body A cast thereon, so as to unite with the tail ends of the jaws, substantially as described. 95

WM. A. IVES.
